(57) **CLAIM**

The ornamental design for a load cell for a scale, as shown and described.

DESCRIPTION

FIG. 1 is a perspective view of an embodiment of the load cell for a scale;

FIG. 2 is a front elevation view of the FIG. 1 embodiment;

FIG. 3 is a rear elevation view of the FIG. 1 embodiment

FIG. 4 is a left-side elevation view of the FIG. 1 embodiment;

FIG. 5 is a right-side elevation view of the FIG. 1 embodiment;

FIG. 6 is a top plan view of the FIG. 1 embodiment; and,

FIG. 7 is a bottom plan view of the FIG. 1 embodiment.

The broken line depiction of a cable in FIGS. 1, 2 and 4-7 is included for the purpose of environment and forms no part of the claimed design.
